Arthur Bessey Smith

Chas. H. Candy Atty:

UNITED STATES PATENT OFFICE.

ARTHUR BESSEY SMITH, OF EVANSTON, ILLINOIS, ASSIGNOR TO AUTOMATIC ELECTRIC COMPANY, OF CHICAGO, ILLINOIS, A CORPORATION OF ILLINOIS

TELEPHONE RECEIVER.

Application filed August 1, 1921. Serial No. 489,006.

To all whom it may concern:

Be it known that I, ARTHUR BESSEY SMITH, a citizen of the United States of America, and a resident of Evanston, Cook County, and State of Illinois, have invented certain new and useful Improvements in Telephone Receivers, of which the following is a specification.

The present invention relates in general to telephone receivers and has for its principal object the provision of a new and improved telephone receiver of the permanent magnet type in which is embodied a new feature or principle of construction which substantially increases the efficiency of the receiver.

In the accompanying drawings, Fig. 1 is a side view of a telephone receiver embodying the invention, with the shell cut away to show the various parts. Fig. 2 is an end view of the same with the receiver cap, diaphragm, and the coil winding removed. Fig. 3 is a side view of the lower end of the receiver without the shell and having a portion of the cup cut away so as to show the internal construction. Fig. 4 is a view of one of the receiver pole pieces showing the core of the magnet coil, while Fig. 5 is a view of the other pole piece.

As illustrated in the drawings, it will be seen that the improved receiver comprises the usual hard rubber shell 1, cap 2, cup 4, diaphragm 12, and permanent magnet 20. To the permanent horseshoe magnet 20 are fastened, by means of the screw 11, the soft iron pole pieces 8 and 9. There is clamped between these pole pieces the end of the non-magnetic cup 5, the end of the latter being recessed slightly in order to maintain the pole pieces in their proper position. In addition to this, the projections 21 and 22, and 23 and 24 on the two pole pieces have corresponding holes in the adjacent portion of the cup and can thus be firmly clamped in position. A detailed view of one of these pole pieces is shown in Fig. 4 and from this figure it will be noted that the pole piece 9 is bent to form a right angle and on this bent portion there is riveted the pin 15. Upon this pin there is wound the coil 10 of the electromagnet. A detailed view of the other pole piece is shown in Fig. 5 and from this it will be seen that the pole piece 8 is so formed that when the receiver is assembled the two lugs on this pole piece will come on the outside of the coil which is

wound on the extended portion of the pole piece 9. This is shown clearly in Figs. 2 and 3. There is a small air gap between the two pole pieces beneath the coil when assembled which greatly increases the efficiency of the receiver, as will be explained fully hereinafter. On either side of the pole piece 8 there are located the terminals 7 and 16 to which are attached the wires leading to the electromagnet. It will be seen that the coil 10 of the electromagnet is located right at the center of the cup where it will have the greatest effect on the diaphragm 12.

Having described the mechanical construction of the improved receiver its theory of operation will now be gone into. The magnetic circuit of the permanent magnet includes the pole piece 9, pin 15, the diaphragm 12, and both sides of the pole piece 8. A certain amount of leakage flux of course will follow the gap between pole pieces below the coil without passing through the diaphragm 12, due to the fact that the bent over end of pole piece 9 is close to the pole piece 8. The effects of the varying magnetic flux produced by the voice currents in the coil of the electromagnet are localized in the pole pieces, that is, the flux generated by the coil is set up in the following circuit: The bent portion of the pole piece 9, pin 15, diaphragm 12, lugs of the pole piece 8, and the gap between the pole pieces. It will be noted that there is but a very short length of iron included in the magnetic circuit which is subject to rapid change of magnetism at conversational frequencies, being merely the two lugs on the pole piece 8 and the pin and angle upon which it rests on the pole piece 9. This magnetic circuit is made up of soft iron having high permeability and does not include, as was the case in the prior receivers of this type, the permanent magnet which is made of hard steel having a relatively low permeability. In the present case there is a leakage path of low reluctance provided by a small gap between the pole pieces so that the magnetism generated by the coil has only to affect the small amount of soft iron in the magnetic circuit including the pole pieces; that is, the current variation in the coil produces a relatively greater change in the attractive force upon the diaphragm than has been formerly the case in the prior receivers of this type. Looking at this from

another angle the effect of the conversational alternating currents is such that when the current is flowing in the coil 10 in such a direction as to assist the magnetism developed by the permanent magnet less of the magnetic flux is shunted by the air gap; that is, there is less leakage flux. However, when the current flows in the coil 10 in such a direction that the magnetism set up by it opposes the magnetism set up by the permanent magnet, more flux is shunted by the air gap between the pole pieces; that is, there is a greater amount of leakage flux.

The structure of this receiver wherein
16. pole pieces of soft iron constitute the main
part of the magnetic circuit which is sub-
ject to the rapid variation of magnetism
produced by currents at conversational fre-
quencies, is very advantageous and this con-
struction produces a most efficient receiver.
20. Other advantages lie in the arrangement
whereby a single coil exerts an attractive
force upon the center of the diaphragm
and also in the construction of the pole
25. pieces so that there is uniform pull on the
diaphragm.

The features of the invention having been described and ascertained what is considered to be new and desired to have protected by Letters Patent will be pointed out in the appended claims.

What I claim as my invention is:

35. 1. In a receiver, a horse-shoe magnet, a diaphragm, a soft iron pole piece extending from one pole of said magnet, a core attached to said pole piece, said core being centrally located with respect to said diaphragm, a second soft iron pole piece extending from the second pole of said per-

manent magnet and terminating in two 40
polar lugs spaced equidistant from said
core, said second pole piece being formed so
that said polar lugs are connected to the
second pole of said magnet by equal length
magnetic paths, and a coil wound on said 45
core between said polar lugs.

2. In a receiver, a permanent magnet, a diaphragm, a soft iron pole piece extending from one pole of said magnet, said pole piece having a bent portion which lies parallel to said diaphragm, a core projecting from said pole piece at right angles to and centrally located with respect to said diaphragm, a second soft iron pole piece extending from the other pole of said magnet and terminating in two equal shaped polar lugs which are parallel to said core, said second pole piece being so designed that the magnetic path from one polar lug to the pole of the magnet is exactly equal to the magnetic path from the other polar lug to said pole, and a single coil electromagnet wound around said core.

3. A receiver having a permanent magnet and a diaphragm, a detachable soft iron pole piece for each pole of the magnet, one piece formed as the core of a coil and extending toward the center of the diaphragm, the other pole piece having two extensions equi-distant from the other pole piece and on opposite sides thereof, said second pole piece being formed in such a manner as to provide parallel paths of equal reluctance for the magnet flux passing from the diaphragm to the magnet. 65 70 75 76

In witness whereof, I hereunto subscribe my name this 26th day of July, A. D., 1921.
ARTHUR BESSEY SMITH.
